WINTER SPORTS VEHICLE

Howard A. Robison, Long Beach, Calif.

Application March 30, 1953, Serial No. 345,347

2 Claims. (Cl. 280—11.39)

The present invention relates to the field of vehicles, and more particularly to an amusement-type winter sports vehicle on which a person wearing skis may travel over a snow-covered surface in a seated position.

In recent years the popularity of winter sports has increased to a marked extent in the United States, and as a result, a demand has been created for new devices to provide thrills not found with the use of conventional skis, toboggans, and ice skates.

The primary purpose in devising my present invention is to provide an amusement device in the form of a vehicle adapted to be used equally well by both experienced skiers and tobogganers, as well as those who are merely novices at winter sports. It will be obvious that the experienced skier will be most proficient from the very first trial of my invention, but each type of sportsman will be assured of new thrills and pleasure by the use thereof.

A major object of my invention is to furnish a vehicle of simplified mechanical structure embodying a saddle on which a person is supported in a straddling position, and when so mounted thereon, may glide over a snow-covered downgrade.

Another object of my invention is to provide a snow sports vehicle of single runner construction, with the vehicle caused to be maintained in a stable upright position by use of skis worn by the operator thereof in a rudder-like fashion.

A further object of my invention is to supply an amusement type vehicle that may be controlled by the operator thereof at all times and is adapted to be braked to a stop by means of skis worn by the operator.

Another object of my invention is to furnish a winter sports vehicle that is easily adjustable to various sizes, thus rendering it ideally suited for individual use or as an amusement device which may be rented to the general public.

Yet another object of my invention is to provide a novel device whereby the winter sports enthusiast may coast down-slope with safety, and on steep downgrades that the most skilled of skiers would negotiate with difficulty without mishap.

A still further object of my invention is to provide a light-weight winter sports vehicle adapted for easy return to the crest of a grade, by means of a particular form of climbing ski most suited for this purpose.

Yet another object of my invention is to provide a novel sports vehicle that may be fabricated from standard commercially available material, does not require extensive plant facilities for its production, and may be sold in the medium priced merchandising field.

These and other objects and advantages of my invention will become apparent from the following description of a preferred form thereof, and from the drawings illustrating that form in which:

Figure 1 is a side elevational view of my winter sports vehicle;

Figure 2 is a plan view of the device;

2

Figure 3 is a side elevational view of one of the climbing skis used in conjunction with my invention; Figure 4 is a plan view of said ski;

Figure 5 is a perspective view of the hinge connection between the vehicle runner and the saddle-supporting frame;

Figure 6 is a perspective view of a novel climbing element provided on my ski; and

Figure 7 is a side elevational view of my vehicle showing the saddle-supporting frame tilted rearwardly, with the skis being used for braking purposes.

Referring now to the drawings for the general arrangement of my invention, in Figures 1, 2 and 7 it will be seen that it includes an elongate runner R that pivotally supports an upwardly and forwardly extending tubular frame F. Frame F serves as a support for an intermediately disposed saddle S and has a U-shaped handle H mounted on the outer extremity thereof. In operation, the user U (shown in phantom line) wearing short climbing skis C, straddles the seat or saddle S whereby the skis are normally disposed on opposite sides of runner R.

The runner R is preferably fabricated from an elongate strip 10 of wood such as hickory that is bent or otherwise formed into a forwardly disposed upwardly extending curved portion 11 as is typical in ski construction. To prevent lateral slippage of the runner R when gliding over hard-packed snow or snow having an icy surface, the lower surface of the runner is preferably provided with a longitudinally extending ridge or groove (not shown).

Frame F is pivotally supported from the upper surface of runner R by a hinge construction 13, the details of which may best be seen in Figure 5. Hinge 13 includes a rectangularly shaped metal plate 14 rigidly affixed to the upper surface of runner R by screws 15. Plate 14 has two parallel, laterally separated side walls 16 extending upwardly therefrom. A transversely disposed bore 17 is formed in each side wall 16 through which a horizontally disposed pin 18 extends. Threads 19 are formed on the ends of pin 18 which are engaged by nuts 20, which nuts serve to removably maintain pin 18 in a horizontal position between side walls 16. A tubular sleeve 21 disposed between side walls 16 is rotatably supported on pin 18.

Frame F is preferably formed from an upwardly and forwardly extending curved tubular member 22, which member has two oppositely disposed transverse bores 23 formed in the lower side wall portions thereof. The sleeve 21 extends through bores 23, with the sleeve and tubular member 22 being connected to one another at their contacting surfaces by conventional means. Should it be desired, the tubular member 22 may pivot directly on pin 18, and be maintained in the desired lateral position between side walls 16 by the use of spacers. The particular construction employed is merely a matter of choice.

In Figure 1 it will be seen that a tubular saddle post well 24 extends upwardly from an intermediately disposed position on the tubular member 22, and is in communication with the interior of tubular member 22. The saddle post well 24 is of such diameter that it slidably engages a portion of the saddle post 25. Saddle post 25 is slidably disposed within the confines of the post well 24. The saddle post is adjustably held in the desired vertical position relative to the post well 24 by a conventional bifurcated clamp 27a of the type used in maintaining bicycle saddle posts at the desired elevation.

The saddle S is preferably of the type employed on bicycles, and as is common therewith, includes a triangularly shaped seat portion 28 secured to the upper portion of the saddle post 25. Clamp 27a includes a bolt 30.

which when tightened, causes the clamp to grip the saddle post 25 with sufficient force to support saddle S in the desired position.

Handle H, as may best be seen in Figure 2, is formed from a generally U-shaped tubular member 40 having a centrally disposed portion 40a. Handle bar portion 40a develops into rearwardly extending members 40b at the outer extremities thereof, each of which has a bicycle hand grip 41 mounted thereon. A curved tubular member 42 extends rearwardly from substantially the mid-point of handle H of such diameter as to be slidably movable within the confines of the outer portion of tubular member 22. It will be particularly noted in Figure 1 that member 42 has the same radius of curvature as tubular member 22. Thus, the handle H is longitudinally movable relative saddle S, but cannot rotate in a plane normal to frame F. A clamp 43 of the same general type as clamp 27a is so mounted on tubular member 22 as to adjustably support handle H in the desired position relative thereto.

It will be particularly noted in Figure 1 that the vertical axis of the saddle post well 24 is disposed forwardly of the axis of the pin 18, with the result that when a user U is mounted on saddle S, the frame F tends to pivot forwardly in a clockwise direction. Frame F may also pivot rearwardly in a counterclockwise direction when a person is disposed on the saddle S. To prevent rearward pivoting of the frame F beyond a predetermined point, a curved resilient stop 44 is affixed to the lower portion of the tubular member 22. When the frame F is positioned as shown in Figure 1, the lower ends 45 and 45a of the resilient stop 44 are disposed above the upper surface of the runner R, but as the frame member F tilts rearwardly, the lower end 45 contacts the upper surface of the runner to prevent further movement of the member 22. Forward movement of the frame F is likewise limited by the end 45a of the stop when it contacts the upper surface of the runner. The position of a person when mounted on my invention may best be seen in Figures 1, 2 and 7. It will be evident from these figures that when a user U is mounted on my invention he may balance himself by using his skis C to contact the snow-covered surface, whereby they serve in the manner of stabilizing rudders. Thus, a user U is supported in a stable, vertical position, as is the vehicle itself, by the three-sided support afforded by the runner R and the two skis C.

The detailed structure of the skis C are best seen in Figures 3, 4, 5 and 6. Each ski includes a short runner 50 having a curved upwardly extending forward end 51 as is conventional in ski construction, and provided with the conventional ski binding 52, the details of which are not shown. The ski binding 52 is disposed on the upper surface of the runner 50 to the rear of the center point thereof.

The structure of the skis C is quite important, as they serve not only to balance the user of my invention when traveling over a snow-covered surface, but as an aid in climbing upwardly to the top of an incline after sliding downwardly thereon. To facilitate the easy transportation of my invention from the bottom to the top of an incline, I provide a climbing hinge 53 on the rearward end portion of each ski, the structural details of which are best seen in Figure 6. The climbing hinge 53 includes a first plate 54 affixed to the rearward upper surface of the runner 50 by screws 55 in a conventional manner. Plate 54 has eyes 54a extending outwardly from the rearward portion thereof, that have a transversely disposed pin 57 extending therethrough. The pin 57 pivotally engages the eyes 58a formed on the upper portion of a second plate 58. The plate 58 is somewhat longer in length than the thickness of the rearward portion of the runner 50 (see Figure 3), and projects downwardly below the lower surface of the runner when the second plate is in an abutting position.

Thus, when the skis C are moving forwardly, the

second plate 58 merely drags over the surface of the snow and does not obstruct the movement of the skis C in any manner. However, when a person wearing the skis C is walking uphill, and the skis tend to slide rearwardly, the resistance of the lower portion of plate 58 which digs into the snow, causes the plate to pivot to the abutting position shown in phantom line in Figure 3. The resistance offered by second plate 58 when in this abutting position is sufficient to prevent any appreciable downhill movement of the skis. Upon occasion it has been found that snow tends to pack between the interior surface of the plate 58 and the vertical rearward edge of the runner 50, and to prevent this I form one or more openings 59 in the upper portion of the second plate as shown in Figure 6. Openings 59, or a series of openings may be used if desired, permit the snow to squeeze outwardly from the position between the interior surface of the plate 58 and the rearward vertical edge of the runner 50 when the plate is subjected to counter clockwise movement.

20 The operation of my invention is extremely simple. The handlebar H and the saddle S are adjusted to a position comfortable for the person mounted on the device. Before mounting my invention the user U places the skis C on his feet securely by means of the ski bindings 52. 25 The vehicle is then taken to the crest of a downhill slope. When properly mounted on the vehicle as shown in Figure 1, the user may easily balance himself due to the three-point support afforded by the runner R and skis C. During a glide if the user desires to turn to either 30 the right or left, he need only to lean in the desired direction and simultaneously move the position of the skis C relative to one another to effect the turn, as is common in skiing. It will be noted that the center of gravity of frame F is forwardly of pin 18, whereby the frame tends 35 to pivot forwardly and downwardly when a user is riding thereon. However, this tendency of the frame to pivot forwardly and downwardly is resisted by the user when he exerts downward force on the skis C. Accordingly, the skis C are always in firm contact with the snowy 40 surface over which the vehicle is traveling and a maximum maneuverability of the vehicle is achieved by varying the position of the skis relative to one another. In the event the vehicle accumulates a more rapid speed 45 than desired, the user may easily and simply brake the vehicle by leaning backwardly in the saddle to transfer his center of gravity rearwardly beyond the pin 18. The frame F will then pivot rearwardly, but with the degree of this rearward movement being restricted by the resilient stop 44 when it comes into contact with the upper 50 surface of runner R. At the same time the user starts to move rearwardly, the skis C are moved into an upwardly and forwardly tilted position, bringing the sharp rearward transverse edge portion 60 of the runners 50 into contact with the snow surface. When the rearward 55 portions of the skis are so disposed, they dig into the snow and serve as a brake to slow down the speed of the vehicle, as may be seen in Figure 7.

Although the snow vehicle herein shown and described is fully capable of achieving the objects and providing 60 the advantages hereinbefore mentioned, it is to be understood that it is merely illustrative of the preferred embodiment of my invention, and that I do not mean to limit myself to the details herein shown and described other than as defined in the appended claims.

65 I claim:

1. A vehicle on which a person may travel in a seated position which includes: an elongate runner formed with an upwardly curved forward end portion; a hinge plate affixed to the upper surface of said runner; a first upwardly and forwardly extending curved tubular member, the lower end portion of which is pivotally connected to said hinge plate; a bicycle-type saddle provided with a clamp; an L-shaped saddle post formed with a first and a second leg with said saddle being clamped to said first leg; a saddle post well, extending upwardly from said

curved member disposed forwardly from the position at which said tubular member is connected to said hinge plate, with said well adapted to slidably receive said second leg of said saddle post; a clamp capable of maintaining said saddle post at the desired elevation relative to said tubular member; a second curved tubular member slidably mounted in the forwardly extending portion of said first tubular member; a transversely disposed U-shaped handle mounted on the outer end of said second tubular member; and a clamp which when tightened maintains said first and second tubular members in the desired relationship relative to one another.

2. A winter sports vehicle for use by a person wearing a pair of short skis on his feet, comprising: an elongated runner formed with an upwardly curved forward end portion; a forwardly and upwardly extending support member; means pivotally attaching the lower end of said support member to the intermediate portion of said runner; stop means limiting rearward pivoting of said support member relative to said runner; a seat secured to the intermediate portion of said support member; and a handlebar secured to the upper portion of said support member, said support member and said seat being so located relative to said runner that said person may sit on said

seat straddling said runner with the latter supporting substantially all of his weight while he uses said short skis for maintaining equilibrium and for braking, said person leaning backwardly during a braking operation so as to transfer his center of gravity rearwardly of the lower end of said support member.
